WRAPPING AND BANDING MACHINE

Francis X. Malocsay, Upper Saddle River, N. J.,
assignor to International Banding Machine
Company, a corporation of New York

Application February 27, 1934, Serial No. 713,116

9 Claims. (Cl. 93—2)

This invention relates to the art of banding and wrapping cigars, and more particularly to the wrapping of transparent wrappers and bands around cigars.

5 It is among the general objects of the present invention to provide an improved wrapping and banding mechanism, which will be entirely automatic in its operation.

In prior copending applications to wit: Serial 10 No. 590,571, filed February 3, 1932; Serial No. 603,815, filed April 7, 1932; Serial No. 608,378, filed April 30, 1932, and Serial No. 653,609, filed January 26, 1933, I have shown different machines and devices for accomplishing similar objects not alone in a general way but also that particular part of the operation with which the present invention is specifically concerned,—the simultaneous feeding of the wrappers and bands.

The present device therefore has for one of its 20 specific aims and purposes, the providing of improved means of feeding cigar bands and wrappers simultaneously to a wrapping and banding position. In one of my previous applications, for example in the wrapping and banding machine, described in Serial No. 653,609, filed January 26, 1933, both the band and wrapper feed mechanisms were located at the rear of the machine, a wrapper being advanced by the feed rollers to a position underneath the band magazine from which a band is placed upon said wrapper, whereupon a reciprocating gripper carries both band and wrapper to a position beneath the wrapping and banding device, and over a cigar, which is raised from underneath into said combined wrapper and band, carrying them upwards 30 into the banding and wrapping position properly. When in this stationary position, the wrapping, banding and sealing operations are performed, and the band will appear on the outside of the 40 cigar wrapper, encircling the same.

The present invention differs mechanically from that disclosed in my copending application in that the wrapper feed rollers are located at the rear of the machine while the band magazine and band feeding device are positioned on the opposite or front side of the machine, separated from each other by the rectilinear cigar feeding and delivery path toward which both devices feed a wrapper and a band respectively in such a way 45 that the band is put underneath the transparent wrapper and is visible therethrough, by means of a reciprocating gripper; thus both the band and the wrapper are deposited at the banding and wrapping position which consequently is located at the crossing point of the band and

5 wrapper conveyor path, i. e. above the reciprocating gripper, and that of the cigar feed and delivery path, the wrapping device itself is positioned above this crossing point and the rest of the operations are somewhat analogous to those mentioned before, with this difference, that the result will be a cigar banded directly within a superimposed wrapper so that the band will be visible through the said wrapper.

Considered more in detail it is among the objects of the present invention to provide a wrapper and band feed arrangement wherein a band magazine and a wrapper roll are placed facing each other and on opposite sides of a straight 10 coursed cigar feeding and delivering path and both adapted to feed a wrapper and band, superimposed upon each other, to a wrapping and banding device located within said path.

Another object is to provide a wrapper and band feeding device which will place a wrapper 20 over a band and both in unison over a cigar in a wrapping and banding position.

Another object of this invention is to devise a novel wrapper feeding device which is adjustable to accommodate wrapper rolls of different 25 width, corresponding to cigars of different circumference.

Another object is to provide a wrapper feeding device adapted to feed wrapper sections from a roll at an equalized tension.

Another object of the invention is to provide 30 novel and self-adjusting means whereby equal wrapper sections are intermittently fed from a roll.

Another object of the invention is to provide 35 means of temporarily stiffening a pliable wrapper band while it is being fed from a pair of feed rollers to the knife and the gripper device of a reciprocating conveyor.

A further object is to provide a novel knife 40 construction for separating wrapper portions from the feed roll, adjacently to the wrapping device, which knife construction will not obstruct or retard the upward motion of the cut-off wrapper end during the beginning of the wrapping 45 operation.

Another object is to provide an adjustable band magazine with a simplified pneumatically operated band picking device which removes one band at a time from the bottom of the band 50 stack in said magazine.

A further object of the invention is to provide a moistening device adapted to moisten the gummed end of a band while it is being picked from the band magazine.

Another object of the invention is to provide a reciprocating wrapper and band conveyor with a novel gripping action.

5 A further object of my invention is to provide a novel actuating mechanism for the last mentioned wrapper and band conveyor.

Another object of the invention is to provide automatic means of preventing the further feed of wrappers when the supply of cigars at the 10 wrapping station temporarily or definitely gives out.

Another object of my invention, corollary to the last named, is to provide automatic means of simultaneously stopping the feeding of bands in 15 such a case.

Other more specific objects and advantages of the apparatus will appear as the nature of the improvements are better understood, the invention consisting substantially in the novel arrangement and correlation of instrumentalities herein fully described and illustrated in the accompanying drawings wherein similar reference characters are used to describe corresponding parts throughout the several views and then finally pointed out and specifically defined and indicated in the appended claims.

The disclosure made the basis of exemplifying the present inventive concept suggests a practical embodiment thereof, but the invention is not to be restricted to the exact details of this disclosure, and the latter therefore is to be understood from an illustrative, rather than a restrictive standpoint. It will be understood that the various features of the invention disclosed may be separately applicable despite their cooperation herein shown.

The invention may be more fully understood from the following description in connection with the accompanying drawings, in which—

40 Fig. 1 is a top plan view of my improved banding and wrapping arrangement, showing the cigar feeding and discharge table, the wrapper feed mechanism on the right hand or rear side of the table and the band feed mechanism on the left hand or front side of the table. The wrapper roll supported on the feed rollers on the right side, as well as the band magazine on the left side, are omitted,—only the brackets supporting the latter are indicated in section.

50 Fig. 2 is a partly sectional elevation, taken along the line 2—2, looking in the direction of the arrows and showing the wrapper roll and feeding mechanism in cross-section, the wrapping device and wrapper and band gripper mechanism in front elevation and the band magazine and pertaining feed mechanism in cross section.

Fig. 3 shows an elevation of the band magazine and band picker as viewed from the rear edge of the machine.

60 Fig. 4 is a view looking at the upper or stationary part of the wrapper knife and the device which serves to stiffen the wrapper band when it comes forth from the front feed rolls.

Fig. 5 is a bottom view of the upper knife showing the runners for guiding the wrapper.

Fig. 6 is a view, partly in section, showing the band magazine and the band conveying mechanism, its gripper being in closed position, having just received a cigar band from the band picker.

70 Fig. 7 shows the band conveyor at the extreme opposite end near the wrapper feed device, with the gripper jaws opened.

Fig. 8 is a sectional view of the gripper device along the line 8—8 of Fig. 7.

Fig. 9 is a bottom view of the upper gripping jaw.

Fig. 10 is a cross sectional view along line 10—10 of Fig. 6.

Fig. 11 is a detail of the band moistening device, 5 shown in sections during the band moistening operation.

Fig. 12 is a similar view of this device, in a position after the moistening.

Fig. 13 illustrates the means of actuating the 10 band moistener.

Fig. 14 is a view, partly in section, showing the mechanism for stopping the feed of bands, while it is ineffective, i. e. while a cigar lies underneath the feeler finger, and prevents its complete de- 15 scent.

Fig. 15 is a similar view showing the mechanism in action, i. e. while no cigar stops the complete descent of the feeler finger.

Fig. 16 shows both the mechanism for operating 20 the wrapper feed and the mechanism for reciprocating the wrapper and band conveyor.

Fig. 17 is a detail, pertaining to the arrangement in Fig. 16, showing the means for stopping the clutch engagement and consequently the 25 wrapper feed when the supply of cigars to the wrapping station is interrupted or ceases altogether.

Fig. 18 is a sectional view along the line 18—18 of Fig. 1, showing an inner end view of the wrap- 30 per feed rollers, also an elevation of the knife and the free-wheeling feeder clutch.

Fig. 19 is a similar view, taken along the line 19—19 of Fig. 1, showing, however, the feeder clutch in section.

Fig. 20 is a detail view, taken along line 20—20 of Fig. 19, showing the inner construction of this clutch.

Fig. 21 is a section taken on line 21—21 of Fig. 19 and showing the tension brake for the feed 40 rollers.

Fig. 22 shows the cam controlled drive of the rocking shaft from which the wrapper feed is actuated.

Similar characters denote similar parts 45 throughout the different views.

Referring more in detail to the figures listed, Fig. 1 shows a top view of the table or frame 1, supporting the various mechanisms as described before.

Character W designates the wrapper feed; X, the band feed and moistening device; C, the cigar feed and D the wrapping and banding station. The cigars are fed in a continuous row from the hopper, not shown in the drawings, but located 55 at the upper end of the table 1 (above what is shown in the drawing of Fig. 1). The type of this mechanism is fully described and illustrated in my former Patent No. 1,653,641, of December 27, 1927, as also in the copending applications, 60 Ser. No. 492,437 (Cigar banding machines), filed October 31, 1930, as well as in Serial No. 519,347 (Cigar handling machines) filed March 2, 1931. From this hopper the cigars are fed into a belt feed, part of which is shown at the top of Fig. 1. 65 This belt feed advances the cigars with an intermittent movement, the rest periods between the forward movements of the cigars being equal to one complete cycle of operations necessary to complete the wrapping and banding of a cigar 70 by the machine. Then the cigars are pushed one by one upon the top of a cigar elevator or plunger where they are covered by the combined band and wrapper, supplied to this location by the communicating conveyors. This location of the 75

cigar is indicated in Fig. 1 at D by dotted lines, and vertically above this is installed the wrapping and banding mechanism, into which the rising plunger carries the cigar, folding at the same time the band and the superimposed wrapper around the three exposed sides of the cigar. This wrapping and banding mechanism is not shown in Fig. 1, but its front elevation, as well as the cigar elevator and plunger, can be seen in the middle part of Fig. 2. The details of the intermittent belt feed, as well as the construction and operation of the wrapping and feeding mechanism, and also the remaining parts of the whole machine, i.e., the parts that belong to the drive and to the delivery of the wrapped and banded cigars, as far as they are not altered and described and shown in their modified form in this specification, can be learned from my co-pending application, Ser. No. 653,609 (Wrapping and banding machine) filed January 26, 1933.

We will now proceed to describe the essential new devices and appurtenances by which the present invention differs from the machines disclosed in my former patents and copending applications.

Wrapper feeding device

This device is illustrated mainly in Figs. 1, 2 and 18 to 21, while Fig. 16 shows the drive for it. A loose roll W (Fig. 2) of regenerated cellulose and of a width corresponding to the required wrapper width for the special kind of cigars handled by the machine is supported by a pair of roller sets, as shown in Figs. 1 and 2. The first set consists of the central pulley 101, fixedly attached to the shaft 100 and the two slidably mounted rollers 102, both provided with an outer flange, adapted to keep the loose wrapper roll in central alignment. The guiding distance between the outer flanges can be adjusted by means of a right and left hand swivel screw 103 which passes through the webs of the three rollers 101 and 102 and also serves to couple them together. The second set comprises the supporting roller 57, provided with two rubber tires 92, spaced so as to guide the outer edges of the cellulose strip. This roller 57 can turn freely on the shaft 59, while below and in eventual contact with it is provided another roller 56, formed with two cylindrical crowns 60, aligned with the rubber tires 92. See Fig. 19. This roller is fixedly secured to the driving shaft 58 on which also the clutch 62 and the sprocket 78 is mounted. Shaft 100 with the rollers 101, 102 is driven from this shaft by means of a crossed belt drive 105, which connects the two grooved pulleys 106 and 104, fixedly mounted on the two shafts 100 and 58 respectively. As shaft 58 is driven in a counter-clockwise direction and actuates the shaft 59 by a pair of gears, 97 and 98, mounted respectively on the two shafts, it is obvious that both shafts 100 and 59 will be rotated in a clockwise sense, thus imparting to the superimposed wrapper roll W a counter-clockwise rotation. The cellulose strip, unwinding from the bottom of the roll, travels around rollers 101, 102 and glides along plate 77 which is fastened on top of bracket 55 which latter serves as support for the bearings, in which the shafts 100, 59, and 58 are journaled. Thence the strip passes between the feed rollers 57 and 56 toward the knife mechanism to be described later. While the rollers 101 and 57, or rather the rubber tired rims of the latter are installed above said plate 77, tangentially in line with it, the roller 56 is placed tangentially below

the same and the space between the latter two rollers is naturally spared out, so that the cellulose strip passing therebetween, touches both rollers, transmitting the rotation of the lower to the upper rollers by friction. The grooved rear belt pulley 106 is slightly smaller in diameter than the driver pulley 104, to create a slight drag in its friction against the wrapper roll and thereby to keep an even tension on the strip of cellulose to be dragged from the roll. Thereby it is prevented that the hind roller through its momentum may loosen up too much of the strip before coming to a stop. Besides this there is provided a little idler 56' in order to keep the wrapper sheet flattened before it enters between the front feed rollers.

As the thickness of the cellulose may vary and a very fine adjustment of the center to center distance of the feed rollers is desirable, in order to regulate the frictional drag of the sheet, provision is made to accurately adjust this distance and thereby to control the forward pull on the wrapper strip. The ends 59a of shaft 59, which, as Fig. 19 shows, are diametrically reduced, are turned slightly eccentrically in relation to the roller axis. These two ends turn freely in the bushings 95 (see Fig. 19) which are journaled in the brackets 93 and 94 (Fig. 19).

These brackets, which also support the hind roller shaft 100, are part of an integral support 30 on top of bracket 55 which can be slidably adjusted by means of the key 54. At one of these reduced shaft ends is secured a winged member 96 by which the shaft ends can be manually turned in their bearings, thereby lifting the eccentric middle part of the shaft slightly when the front end of a new cellulose strip is inserted. Thereafter, the roller 57 which turns freely on the non-rotating shaft 59, is allowed to drop into frictional contact with the cellulose strip and the underlying metal roller 56. Furthermore, the roller 57 is driven from the clutch shaft through the spur gears 98 and 97, each of which is fixedly attached to its adjacent feed roller.

The driving device for the feeding unit which is all supported on the bracket 55 will be described later in connection with the reciprocating conveyor drive. The bracket 55 is adjustably supported on the table 1, by means of clamp bolt 123 which passes through the slot 122. See Fig. 2. 50

Wrapper cut-off device

In my former patents and applications which disclosed a wrapper cut-off device wherein the wrapper strip, fed from a roll, was cut off in lengths, regulated by the length of the cigar, by means of a scissor-like cutter, the upper knife or blade was the moving part, the strip being fed over the lower or stationary blade. As in the present arrangement there is no longer a band feed device interposed between the wrapper feed and the wrapper folding mechanism, but the cut off wrapper section, being placed already in proper position over the cigar and the band, is immediately carried upward by the cigar elevator of 60 the wrapping mechanism, the movable upper blade would obstruct this upward movement. The cutting action is therefore reversed in this construction, the upper blade being stationary, consisting of a narrow ledge only, the lower blade 70 being hinged and swinging upwardly to cut off the wrapper from below (see Fig. 18).

As the pliable wrapper strip, issuing from between the feed rollers 57 and 56 has to be fed forwardly over the knife pit and the reciprocating

ing carriage or gripper device in a horizontal straight course for more than a cigar length, this could not be accomplished without some means of stiffening the forthcoming strip by slightly bonding it back and forth in a transverse direction. This means is illustrated in Figs. 4, 5 and 18. Under the upper or stationary knife 108 which is secured to bracket 55 by screws 107 (see Fig. 1) is a thin plate 160 provided with two downwardly extending ridges or guide strips 161, while the wrapper-supporting plate 17, mentioned before, is provided with a similar upwardly extending ridge 162. At the inner end, where the wrapper sheet issues from the feed rollers, these ridges are tapered off, as indicated in Fig. 5 (161a) to facilitate the gradual curving of the sheet, and Fig. 4 indicates in which form the same passes over the knife gap and the band gripper device.

20 The stationary knife 108 is provided with a feeler finger 116 (see Figs. 2, 5, and 18) either integral with it or fixedly secured to it, adapted to pass between the rubber tires 92 and guide the wrapper strip by its protruding lip 116a, so as to prevent its premature buckling up in the center.

25

The cutting-off mechanism is actuated in the following manner. Pivoted at 108 (see Fig. 18) is the movable knife blade 110, clamped to a one-armed lever 111, which carries a pin 113 to hold the blade in proper relation, while a bolt 114 passes through a hollow rocking shaft 112, (see also Figs. 19 and 1) journaled over and crossing the clutch shaft 58. The bearing for this shaft is an integral part of the bracket 34. At the other end of this bolt is threaded a nut 117 cushioned on a little coil spring 118, by means of which the movable knife blade can be tightened in relation to the upper or stationary blade 108 to insure and regulate a proper shearing action. The free end of arm 111 has a stud 119 to which the forked end 121a of the connecting rod 121 is linked by a universal joint 120 while the lower end of rod 121 is pivoted to a stud on a cam lever, actuated by a special cam on the main cam shaft of the machine, but as this sort of drive forms a claimed part of my former applications, above listed, it is not shown in detail here.

Band feeding and moistening device

50 Secured to table 1, on the front side of the machine, are the two brackets 2-2 (see Figs. 1, 2, 3 and 6) which support the band magazine. Slidably journaled therein are the two parallel shafts 4 and 5 which carry the band guides 6 and 7. Band guide 6 is fixedly secured to shaft 4 and slidably supported by shaft 5, while band guide 7 on the contrary is fixedly secured to shaft 5 and slidably supported by shaft 4. Also carried by bearings in the brackets 2-2 is a left and right hand screw 8 on which the band guides 6 and 7 are threaded in opposite senses, so that, when this swivel screw, which has smooth end trunnions within its bracket bearings, is rotated, the two band guides either approach each other or are farther separated. The screw 8 has a knurled knob 9 at one end (Fig. 3) and it is evident from the foregoing description, that by manually turning said knob the band guides may be adjusted to any length of the cigar band required. The horizontal cross section through the guides 6 or 7 shows a channel form to accommodate the ends of a cigar band and are in themselves adjustable by means of inlaid shim plates, (not shown) which can be pushed inwardly or released by screws 10, imbedded in the slidable supports of

the band guides, said screws being manually operable by the knurled knob, forming their outer ends. This latter adjustment, however, may be effected also by other means, such as shown in my copending application, Serial No. 653,609, and forms no claimed feature of this invention. At the foot of each band guide the bands are supported by little pins 11—11 which prevent a spontaneous discharge of the same. 5

A water reservoir 27 is adjustably secured to 10 table 1 by a screw 28, which clamps a slotted lug 29 which is integral with the bottom of this container to the edge of table 1. See Figs. 11 and 12. The horizontal screw slot (not especially shown) in the lug permits the adjustment of the reservoir toward and away from the center of the band magazine to accommodate bands of various length. In the end of the water reservoir which faces the wrapping device is provided a brush 30, held upright by a perforated casing 42 and located so as to be in line with the suction end of the band picker 12 to be presently described. The water rises in this brush by capillary attraction. 15 20

Journalized in the brackets 2—2, right across the 25
water reservoir, is a rocking shaft 3, and keyed
on it or otherwise fixedly secured is the band sep-
arating member or "band picker" 12 (see Figs.
1, 2, 3) a hollow boxlike little air chest, with a 30
nipple 14 and air hose 15 on the bottom and a
row of suction holes 13 in the top surface of the
free end which faces the center of the bottom
band of the stack, held in the band magazine.
The middle portion of the suction surface is
slightly depressed, as shown at 16, to facilitate the 35
separating of the stacked bands. The hose 15
leads to an automatically controlled valve (not
shown) which controls the suction furnished by
an exhaust pump. This suction chest, swung up
and down by the rocking shaft 3, is adapted to 40
pick one cigar band after the other from the bot-
tom of the magazine stack and deposit it so that
it can be taken up by the gripper jaws. Secured
to an end of the rock shaft which projects from
the bearing 2 is the crutch lever 31 (see Figs. 1 45
and 13 mainly) which serves the purpose of
raising or lowering the band-depressing finger 32.
As may best be seen from Figs. 14 and 15, a
bracket 34 with a forked bearing is mounted in
line with the brackets 2—2, but arranged in such 50
a way that this bearing 34a, 34b is opposite and
parallel to the rocker shaft 3. In this bearing
is rotatably supported a shaft 33 whose pro-
truding end is bent and offset at right angles and
shaped like a crank, bearing at its extremity the 55
finger 32. In the gap which is formed between
the two bearing portions 34a, 34b, a collar 35
with a set screw 36 is fitted around the shaft 33.
By means of this collar the shaft 33 may be ad-
justed in an axial as well as in a rotary direc- 60
tion. By the first adjustment the finger 32 is
aligned with the reservoir brush 30 which in turn
ought to be exactly underneath one end of the
cigar bands stacked in the reservoir. A coil
spring 37, fastened with one end to the set screw 65
36, with the other end to an upright post or pin
38 of bracket 34, tends to keep the finger 32
normally depressed upon the brush 30, while the
crutch lever 31 when swinging upwards, raises
the cranked shaft end and thereby the finger 70
32, so that the gummed end of a cigar band,
dropping from the reservoir, may directly land
upon the wetted brush whereupon the released
and spring-actuated finger 32 will press this 75

band end firmly against the brush. When the band picker 12 is in its raised position, arm 31, keyed on the same shaft is likewise raised, upholding the presser finger 32 against the tension of spring 37 and keeping it out of the way of the descending cigar band. When the band picker 12 swings down again, the air suction which at this time is turned on, withdraws a band from underneath the stack and from the supporting pins 11, depositing it with the gummed end upon the brush where it is moistened by the pressure of finger 32. Then the band picker and likewise the band pressing finger 32, lifted by crutch lever 31, is swung upwards, about $\frac{1}{8}$ ", bringing the band in line with the reciprocating band gripper 153, to be described later, at the same time shutting off the air suction. When the gripper has removed the band from the picker, the rocker arm 3 swings the band picker as well 20 as the arm 31 and the finger 32 fully back to their raised position, ready to release a new band.

The rocking motion of shaft 3 is effected by a cam and lever device actuated by the main drive of the machine. See Fig. 17. Secured at the right hand or delivery end of the working shaft is the lever arm 17 to the end of which is fastened, by means of stud 18, the connecting rod 19, the lower end of which has a stud 20 which is linked to one arm of a bell crank or 30 double arm lever 21, mounted on the shaft 22 while the other arm of this lever carries a roller 23 which by the tension of a spring 26, connecting the lever 21 resiliently to a fixed point, is constantly pressed against a cam 24, fixedly mounted on cam shaft 25.

Band gripper mechanism

A rail 150, consisting of a bar of rectangular cross-section, mounted on its narrow side, spans the path along which the cigars are travelling, and is bolted in the center to the upper leg 151a of an inverted angle bracket 151 which itself is fastened by bolts 152 stationarily to the main frame 1 of the machine (see Figs. 1, 2, 3, 6, 7 and 16). On this rail is slidably mounted the gripper frame 153 which partly surrounds the bar 150 in a manner best seen from the right hand side of Fig. 14, and is itself attached to a link of the sprocket chain 164 by which it can be reciprocatingly drawn back and forth over the rail 150. This drive will be described in detail later on. From the rectangular bed-plate which forms the top of the gripper frame 153 and surrounds the upper edge of the rail 150 in the form 55 of a sliding channel, rise four upstanding lugs, one at each corner, 190, 190 at the wrapper feeding end and 189, 189 at the band feeding end. The sliding member 179 is confined and guided between these lugs and comprises a flat rectangular slide 179a and a square shank 179b integral with and rising from this slide which carries on its top a peculiarly formed tongue (shown in detail in Fig. 9) integral and solid with it and serving as the upper or stationary gripper jaw 180. An inserted piece 191, fastened with screws 60 between the lugs 189, serves as the upper guide plate for the slide 179 and encases a spring tension button 193 which exerts a slight friction upon the sliding plate and tends to prevent its spontaneous dislocation after being shifted from one stop to the other. See Figs. 7 and 8. Similarly an inserted piece 192 between the rear lugs 190 serves as the rear top guide. This piece, however, might be cast integral with the frame 70 and the lugs, if preferred.

The lower movable gripper jaw 183 whose top view is shown in Fig. 8 and cross section in Fig. 10, consists substantially of a forked piece or a square rectangular pad with two ears at the end which embrace and are linked to the shank 179b of the stationary jaw member by means of the driven stud 182. Another stud or pin 184 passes through the free end of the gripper jaw and its protruding end is linked to the depending arm 185 which in turn is pivoted to the free end of bracket 187 by stud 186, said bracket being fixedly attached to the gripper frame 153 by screws 188, as can be seen from Figs. 7 and 8. At the front end of the rail bar 150 is provided a stop 197 and at the rear end a similar stop 198. If now the gripper frame is carried over the sliding rail 150 by the drag of the chain 164 toward the band feed device while the gripper jaws are in the position, shown in Fig. 7, and the band picker 12 holds a band extended into the path of the oncoming gripper, the upper jaw 180 will pass over the band while the lower jaw 183 passes underneath it. The gripper device then continues to move to the left until the projecting end of the slide bar marked A (Fig. 7) strikes the stop pin 197. This brings the bar to a stop, while the gripper frame 153 continues its travel for a very short distance yet (due to the chain operating mechanism) until it reaches the position indicated in Fig. 6. During this short extension of the motion of the frame the bar 179, although held stationary, is pushed backward in its bearings, i. e. in relation to the frame. The upper jaw, being integrally attached to the slide bar, has also come to a stop but the still 35 forwardly moving frame with the bracket 187 straightens out the link 185, thereby raising the free end of the lower gripper jaw and clamping the ungummed end of the band firmly, while the suction at the same time is cut off the band 40 picker. The latter having released the band, the gripper frame with parts in the position shown in Fig. 6, conveys the band to the right until it reaches the position where the band is underneath the band tucking finger (marked F, Fig. 2). 45 There the protruding right hand or rear end of the slide bar, marked B (Fig. 6) strikes the stop pin 198, comes to a stop, while the frame 153 still advances for a very short distance, thereby lowering the free end of the gripping jaw and 50 releasing the band. The latter is carried away with the superimposed wrapper by the cigar which is elevated from below by the plunger, forming a part of the wrapping mechanism. 55

It remains to describe certain mechanical details of the gripper jaws. As the lower jaw is pivoted on pin 182 and alternately swings up or down through a small arc, there must of course be enough clearance provided between the underside of the jaw and the sliding bar 179. As 60 the cross section through both jaws in Fig. 10 shows, they do not meet with straight horizontal gripping surfaces but show a peculiar reciprocal indentation. The lower jaw has a deep recess 200 into which a short projection 202 of the upper 65 jaw fits. Adjacent to this, toward the band side, the lower jaw presents a narrow square cornered tooth 203 with a sharp edge 204 over which the ungummed end of the band is creased when the jaws close. Owing to variations in cigar sizes, 70 the bands are sometimes a little too long for smaller cigars and it was found that crimping and bending down of the ungummed end of the bands helps to fold and seal the ends properly. The inner portion of the lower jaw, adjacent to 75

tooth 283 is recessed, as indicated at 189, except that across this recessed part a ridge 194, having a wedge shaped upper edge, as indicated in Fig. 7, is provided, which edge fits into a corresponding groove 195 in the upper jaw. This secures a firmer grip upon the band. Finally, adjacent to the lug 188, a tongue 196 (Fig. 6) projects from the inserted guide piece 191, and when the jaws are opened, as in Fig. 7, serves to guide 10 the band over the sharp edge of the ridge 194.

Reciprocating drive for wrapper and band feed

The wrapper feed is operated by a chain drive 15 79 (Figs. 1, 2 and 16) which engages a sprocket 78 forming an integral part of the hub of the clutch cup 62, mounted loosely upon the sleeve 61 on the clutch shaft 58, on which the lower feed roller 56 is fixedly mounted, as described 20 before. The clutch is of a well-known free-wheeling type, wherein a number of spring-actuated balls 68 are each encased in a wedge-shaped clearance, formed between a clutch member 64, fixedly mounted on the shaft 58 by the 25 key 63, and the cup-shaped end 62a of the member 62. Looking at Fig. 20 it is apparent that if the cup rim 62a is turned counter-clockwise it will wedge all three balls 68 into the pointed ends of the clearances and thereby force the 30 inner member 64 to rotate in a counter-clockwise sense; also, if the cup is turned clockwise it will force the balls into the wider ends of the clearances (against the tension of the springs 65a) thereby lessening the friction, and permitting a 35 free wheeling action of the cup over the clutch member 64. The projecting end of shaft 58 is threaded and over it is fitted a flanged thimble 66 which serves as anti-friction bushing for the loosely mounted ratchet wheel 53 whose purpose 40 and function will be explained later.

In order to prevent any excessive rotation of the feed rollers 56—57 by their momentum, after the clutch has been released, a spring tension 45 brake 74 (see Fig. 21) is provided which has a retarding action on the hub 56a of roller 56 and is of well known construction. The brake is kept from turning with the shaft by a pin 76 which anchors the brake band to the supporting plate 77.

50 The chain 79, formerly mentioned, is fastened with one end to a bracket 84 by means of stud 83 (see Fig. 16). Bracket 84 is fastened to the frame 1 by screws 85—85. Then the chain forms a downward loop over the floating sprocket 86, 55 passes upwardly over the fixed sprocket 78 on the clutch hub 62 and goes to the spring drum 88, where it is anchored to a stud 81. This drum is separately mounted on a stud 82, behind the clutch shaft and encases a clock spring (not 60 shown), one end of which is secured to the stud 82 and the other carried by a clip on the drum interior. The sprocket 86 is mounted to turn freely on a stud 87 provided on the free end of arm 88 secured to rock shaft 89 which is supported by suitable bearings in frame 1. Secured to an outer end of rock shaft 89 is an arm 90 (see Fig. 22), its free end being provided with a stud 91. A connecting rod 93 is linked with one end to this stud and with the other end to a swivel 65 stud 181 which is adjustably seated in a diametrically located groove 206 of the disk 205, fixedly attached to the end of the cam shaft 204 of the machine. The rocking of shaft 89 imparts an up and down movement of arm 88 which results in 70 alternately releasing or hauling in of chain 79, 75

Thus clutch cup 62 when rotated in a counter-clockwise direction will actuate clutch member 64 and thereby the feed rollers 56, 57, simultaneously winding up the clockspring within the drum 88, but when released, the clutch will be disengaged and the wound-up spring will pull the chain back and the arm 88 upward again, while the clutch cup 62 rotates freely around the member 64, the clutch shaft 58 meanwhile remaining stationary. It is also apparent, that the length 10 of wrappers to be fed from the roll can be controlled by adjusting the eccentricity of stud 181. The reciprocating movement of the gripper frame 158 is effected in the following manner.

As said before, the frame is attached to a link 15 of the sprocket chain 164 (Fig. 16). The horizontal rim of this chain is guided over the two sprockets 165 on stationary stud 166 at the front and sprocket 167 on stud 168 at the rear of the machine frame 1. The downward extending portion 20 of the chain at the rear supports a counterweight 169 which serves to pull the chain and gripper frame automatically from the band supplying position X to the wrapping position D (Fig. 2) when the pull at the front end of the chain is 25 released. The front end of the chain 164 is looped around the floating sprocket 170, freely rotatable on stud 171, secured in the free end of curved lever 172, which is loosely mounted on rock shaft 89. This lever has a lateral ear or 30 extension 173 which carries a stud 174 on which is linked a connecting rod 175, leading to a stud 176, mounted eccentrically on a disk 177 which is 35 rotating at the end of a shaft 178, journaled in frame 1 and driven by a chain and sprockets from the main cam shaft of the machine (not especially illustrated). The rotation of the shaft 178 and the disk 177 imparts a reciprocating swing around shaft 89 to the loosely mounted lever 172 which thereby swings the sprocket 170 in an arc 40 around and below the shaft, thereby pulling the chain and the attached gripper frame toward the band feeding position, while on the return swing the weight 169 helps to return the frame together with the chain toward the banding and 45 wrapping position.

Device for stopping the band and wrapper feed when the supply of cigars is interrupted

With the former cigar wrapping and banding 50 machines there used to be sometimes a considerable loss of material involved, when for some reason or other the supply of cigars was interrupted while the supply of bands or of wrappers continued. Not alone that wrapping and 55 banding material was wasted but the loosely handled enveloping material without any substantial core in them was liable to clutter up the operating parts and get enmeshed into the machinery, thus occasioning eventual interruptions of the 60 smooth working of the machines. These drawbacks are overcome by the installation about to be described.

At right angles to the band feeder rocking shaft 3 and the parallel rocking shaft 33, there is installed a rock shaft 39 which is journaled in a forked bearing 41—41 of a bracket 43, bolted to frame 1, with both ends of the shaft protruding from the bearings. At one end, where the shaft points toward the cigar feed conveyor, is secured 70 an arm 40 which has at its end a crutch-like extension 40a, adapted to serve as a feeler finger, dropping down upon the cigars, as they are fed successively into their last position, before being delivered into the banding and wrapping posi- 75

tion (see Figs. 1, 11, 12, 13, 14 and 15). At the opposite outer end is provided a downwardly extending arm 44, which at its end carries a stud 44' to which a connecting link 45 is attached, leading to a cam lever, actuated by a cam (not shown) which gives to the rocking shaft and the attached feeler arm an up and down movement. The touch of the feeler finger is lightened by a coil spring 149 inserted between the outer bearing 41 and the arm 44, said spring being attached at one end to the bearing bracket and at the other end to the downwardly extending arm 44 (see Figs. 1 and 13). At the same time the arm 44 is keyed on the shaft by suitable means in such a way that in addition to the rocking motion which is communicated from the lever connection 44-45 to the feeler finger 40 there is a short dead motion of arm 44 in relation to the shaft 39 possible, in case that the downward movement of the finger is checked before it reaches its lowest possible position. Normally this is the case, as the descent of the finger is stopped by the cigars which are successively pushed in its path, as can be seen in Fig. 14. If, however, it should happen, that no cigar is present, the feeler finger descends to a lower level, as Fig. 15 indicates, and the following device gets into action.

To shaft 39 is secured the arm 46 by being keyed or otherwise fixedly attached between the bearings 41 (Fig. 1). In front of this arm is a cross-shaped latch 47, pivotally fastened in the bracket 34 at 47a and with three branches, 47a, which rests upon the cushion spring 47'; 47b which acts as a stop, and 48 which has a tapered off top, adapted to engage a lateral projection or nose 49, integral with crutch lever 31, which nose is adapted to lock latch 47 in place as long as it bears down upon it, as Fig. 15 shows. If arm 46 is swung down deep enough by the descent of the feeler finger 40, it depresses the latch branch 47a, compressing the spring, and swings the upper end 48 toward the lever 31 which, as explained before, controls the band pressing finger and is also, through the shaft 3, coupled with the band picker 12. When these two therefore are in their highest position, the end 48 slips underneath the nose 49 and locks the rock shaft, preventing thereby further feeding and moistening of bands. At the end of shaft 3, the connection with the cam-controlled rod 19 is, as Figs. 16 and 17 show, made in such a way that rocking movement of arm 17 which is mounted loosely on shaft 3, is in this case taken up by the dead movement of pin 17a, fastened to 17, within the slot 50c in the bell-crank 50, which latter is fixedly mounted on the end of shaft 3. Only when the arm 31 is released, the spring connection 17b which tends to draw the free leg of the bell-crank toward the connecting rod 19, at the same time keeping the pin 17a in the lower end of the slot, makes the arm 17 and the bell-crank 50 oscillate in unison, thus imparting a rocking motion to the shaft 3. Although, with the arm 31 locked in its upper position, the feeler finger continues its up and down motion, the end 48 of the latch will be able to slip clear of nose 49 only, by the help of spring 47' when a cigar interferes with the complete downward movement of the feeler 40. During each cycle of operation, the highest point of cam 24 imparts in spite of the interlocking action a very slight rocking motion to the shaft 3 which is just enough to let the end 48 slip out from underneath the nose 49, if during the lift of the arm 31 the arm 46 is not sufficiently lowered to keep the spring 47' from expanding.

We will now consider by what means the feeding of wrappers is stopped simultaneously, if the rocking shaft 3 is locked.

To the free end of the slotted bell crank 50 is linked the bar 51 (Fig. 16) which is guided on its far end by a flanged collar 68, fastened by a through-pin to the shaft 58 of the feed roller 56 (Figs. 18 and 19). The bar carries a pawl 52 which engages the teeth of ratchet wheel 53 (mentioned before). Collar 68 has a lateral projection 69 which extends into a notch 70 in the hub 71 of the ratchet wheel. A cushion spring 72 located in collar 68 tends to keep the ratchet wheel 53 in its relative torsion against collar 68 and the clutch member 64, i. e. ratchet wheel 53 can be turned clockwise against the tension of spring 72, as far as the clearance of the projection within the notch 70 will permit. The ratchet wheel 53 carries three projecting pins 73 (Figs. 19 and 20). If it is turned clockwise in relation to the clutch member 64, these pins will retain the rollers (or balls) 65 up in the wider portions of the recesses, against tension of springs 65a, and will prevent their engagement by the chain-driven clutch member 62. Thus, when the bar 51 and pawl 52 keeps the ratchet wheel in clockwise tension against the clutch member 64, the clutch is made inactive and any further feeding of the wrappers is stopped. Again, as soon as rocker shaft 3 is lowered again by the removal of catch 48, the pawl 52 is simultaneously withdrawn and clutch shaft 58 starts rotating intermittently again.

Gumming attachment for wrappers

35

Wrappers made of regenerated cellulose are commonly sealed by heat application to the overlapping rims whereby the moisture-proof coating of the cellulose is partly fused and made adhesive; furthermore the band, if placed on the outside, also helps to keep the wrapper closed. If, however, as in this case, the band is placed directly on the cigar, some manufacturers insist on using a special adhesive which is known by the trade name of Cellusolve. This composition is also known by the name of "ethylene glycol monomethyl ether", which attacks the moisture-proof coating, making it adhesive. Very little of it needs to be applied, as it spreads quickly under heat and it produces a very reliable seal. 50

Thus all the enumerated objects of the invention are obtained in an efficient, economical and simple manner and all the mechanical devices described are coordinated to automatically and synchronously perform the functions required. 55

It is obvious from the foregoing detailed description of my invention, that I have produced a novel cigar wrapping and banding machine, having coordinated mechanism to automatically apply a cigar band around a cigar and wrap a transparent wrapper over it so that the band is visible through the wrapper, said mechanism including means while wrapping the band and wrapper around the cigars to cause the ends of the band to be properly overlapped before the ends of the wrapper are overlapped so as to allow the wrapper to be removed without removing the band. 60

In accordance with the provisions of the patent statute, I have described my invention, but I desire it understood that it is not confined to the particular form shown and described, the same being merely illustrative, and that the invention can be carried out in other ways without departing from the spirit of my invention, and there- 75

fore, I claim broadly the right to employ all equivalent instrumentalities coming within the scope of the appended claims and by means of which, objects of my invention are attained and new results accomplished, as it is obvious that the particular embodiments herein shown and described are only some of many that can be employed to attain these objects and accomplish these results.

10 Having now described my invention, what I claim and desire to secure by Letters Patent, is:

1. In a cigar wrapping and banding machine, comprising a wrapping and banding device, adapted to wrap and band cigars at a single station and a wrapper feeding device, adapted to guide separated wrapper portions from a loose roll of endless wrapper material directly into said wrapping and banding device, means to intermittently feed wrapping material to the wrapping station at equalized tension, said means comprising a pair of supporting friction rollers for the loose wrapper roll, one serving as a driven delivery roller, the other one as an idler, said driven roller being of slightly smaller diameter than the idler, thereby causing a slight drag on the endless sheet to be unwound between the roll and the driven roller, and eliminating any tendency to unwind ahead of the length drawn by said roller when the drive is stopped.

2. In a cigar wrapping machine, the combination with a pair of friction rollers, adapted to deliver between them a wrapper portion from an endless wrapper roll to a wrapping station; of self-adjusting and automatic means to intermittently deliver wrapper portions of any required length from these rollers, said means comprising a free wheeling and self-releasing clutch, axially coupled to one of said friction rollers and adapted to drive said roller in the direction of wrapper delivery only, a chain and sprocket drive, adapted to rotate said clutch in either direction, a drum, to which one end of the chain is tangentially attached and containing a clock spring, adapted to be wound up by the pull of said chain when by the rotation of the chain-actuated clutch the friction rollers deliver a portion of wrapping material, and means to alternately pull and release the other end of the chain, the spontaneous unwinding of the clock spring causing the return of the chain and the clutch into its starting position.

3. In a cigar wrapping and banding machine, the combination with a wrapper feeding device, adapted to deliver a wrapper sheet on top of a cigar and a distant band supply device; of a reciprocating conveyor, provided with a gripper mechanism, adapted to fetch a band from said supply device in an opposite direction from that of the wrapper feed, crimp the ungummed end of the band and insert said band between the cigar and the wrapper sheet before the latter comes into contact with the cigar.

4. In a cigar wrapping and banding machine, the combination with a wrapper feeding device, adapted to deliver a wrapper sheet on top of a cigar and a distant band supply device; of a conveyor, provided with a gripper mechanism, adapted to fetch a band from said supply device in an opposite direction from that of the wrapper feed, crimp the ungummed end of the band and insert said band between the cigar and the wrapper before the latter contacts the cigar, said conveyor adapted to travel reciprocatingly between two stops, one near the band supply

device and one at the end of the conveyor course, adjacent to the cigar, and means cooperatively connected with said stops, to close the gripper over the band when the conveyor reaches the first stop, and to open the gripper and release the band, when the conveyor reaches the second stop.

5. In a cigar wrapping and banding machine, the combination with a wrapper supply device, adapted to deliver a wrapper over a cigar in a wrapping and banding position, a distant band supply device and a reciprocating conveyor, adapted to fetch a band from the band supply device and insert it between the cigar and the wrapper before they come into actual contact; of a chain and sprocket drive to intermittently actuate the wrapper supply device, a separate chain and sprocket drive to actuate the reciprocating conveyor, tension means cooperatively connected with said chain drives and adapted to store up potential energy by the action of the chain drives during the operative phase and to spend said energy during the inoperative phase, restoring thereby the chain drives respectively to their initial position before the operative phase.

6. In a cigar wrapping and banding machine, the combination with a wrapper supply device, adapted to deliver a wrapper over a cigar in a wrapping and banding position, a distant band supply device and a reciprocating conveyor, adapted to fetch a band from the band supply device and insert it between the cigar and the wrapper before they come into actual contact; of a chain and sprocket drive to intermittently actuate the wrapper supply device, a separate chain and sprocket drive to actuate the reciprocating conveyor, tension means cooperatively connected with said chain drives and adapted to store up potential energy by the action of the chain drives during the operative phase and to spend said energy during the inoperative phase, restoring thereby the chain drives respectively to their initial position before the operative phase, said chain drives being so coordinated that their active and inactive phases synchronously coincide.

7. In a cigar wrapping and banding machine, the combination with a wrapper feeding device, adapted to deliver a wrapper sheet on top of a cigar and a distant band supply device; of a reciprocating conveyor, provided with a gripper mechanism and adapted to fetch a band from said supply device and insert it between the cigar and the wrapper sheet before the latter comes into contact with the cigar, said gripper mechanism having means to crease the ungummed end of the band in a direction to bring it nearer to the cigar body when said band is folded afterwards around the cigar.

8. In a cigar wrapping and banding machine, the combination with a band feeding device, comprising a band magazine and a reciprocating band picker, adapted to abstract a band from said magazine by suction; of means to stop the feeding of further bands from the magazine when the supply of cigars to the machine is interrupted, said means comprising a feeler finger which intermittently contacts the cigars while they are fed into the banding mechanism, an escapement device connected in such a way with the reciprocating means of the band picker as to block their free movement when interfering, and cooperating means whereby the feeler finger, when missing the contact with a cigar, will cause the interference of the escapement device with

the reciprocating movement of the band picker.

9. In a cigar wrapping and banding machine, the combination with a band supplying device, comprising means of automatically stopping the supply of bands when the supply of cigars to the machine is stopped, and a wrapper supplying device, actuated by a free-wheeling clutch, adapted to set said wrapper supplying device in operation only when rotating in one direction; of automatic means to simultaneously stop the

wrapper supply when the band supply ceases, said means comprising an escapement device adapted to prevent the rotation of the clutch in the operative direction when interfering, and coupling means to cooperatively connect said escapement device with the automatic stopping means of the band supply device so as to cause the synchronous interference of the escapement device with the free rotation of the clutch. 5

FRANCIS X. MALOCSAY. 10
